UNITED STATES PATENT OFFICE.

CHARLES HARMON, OF SENECA COUNTY, OHIO.

WELL BORING AND DRILLING MACHINE.

SPECIFICATION forming part of Letters Patent No. 236,492, dated January 11, 1881.

Application filed June 1, 1880. (No model.)

To all whom it may concern:

Be it known that I, CHARLES HARMON, of the county of Seneca and State of Ohio, have invented certain new and useful Improvements 5 in Well Boring and Drilling Machines; and I do hereby declare the following to be a full, clear, and exact description of the invention, such as will enable others skilled in the art to which it pertains to make and use it, reference 10 being had to the accompanying drawings, which form part of this specification.

My invention relates to well boring and drilling machines; and it consists in an adjustable walking-beam, which, in combination with a 15 cam, is adapted to increase or lessen the drop of the drill; also, by an arrangement of pulleys, whereby the drill itself is permitted to drop through a greater space than that through which the end of the walking-beam drops at 20 the same time; also, in mechanism by which the drill is lowered as it cuts its way through the rock or earth; also, in an arrangement by which the feeding mechanism is disconnected and the drill permitted to drop until it reaches 25 the bottom of the hole; also, in an improved mechanism by means of which the spool carrying the rope connected with the sand-pump is operated, and upon the same shaft the mechanism for raising the drill may be connected. 30

In the drawings, Figure 1 is a view, in elevation, of a well-boring machine constructed according to my invention, with certain parts of the frame broken away in order to show 35 the interior of the mechanism. Fig. 2 is a plan view of the same. Fig. 3 is a detached view, showing the mechanism by means of which the drill is raised and lowered. Fig. 4 is a plan view of the main driving-shaft, showing 40 the pulleys and clutches operated thereon.

In the said drawings, A represents a frame adapted to receive and contain the operative parts of my device. B represents the main shaft, upon which is carried the main driving-wheel B' and cam C, both of which are 45 permanently keyed to the main shaft B. Power is communicated to the mechanism for operating the drill, raising and lowering it, &c., by the main driving-wheel B', through the pulley B² upon the shaft D. The office of the cam C is to raise the end of the walking-beam E and

permit it to drop at each revolution of the shaft. Upon one end of this walking-beam E is placed a small pulley, adapted to bear upon the cam C. Upon the other end of this walking-beam is a second pulley, under which the rope connecting the windlass with the drill passes. This walking-beam is pivoted at or near its center, as shown at F. This pivot or fulcrum F is adapted to be raised or lowered 55 by means of a screw passing through it, and operated by a crank, F', at the top of the frame. This adjustable feature of the fulcrum or pivot upon which the walking-beam turns I consider as an exceedingly important feature 60 of my invention, as by its use the depth of the fall of the drill may be regulated. If the fulcrum is raised the drop of the drill will be less; if it is lowered this drop is thereby increased. 70

Upon the shaft D, I place a spool, G. Upon this spool is wound the rope or chain used in raising or lowering the sand-pump. When not in use the shaft turns independently within it. When it is desired to operate this spool 75 the clutch g upon its side (see Fig. 4) is engaged with its counterpart b. The pulley B² is also hung loosely upon this shaft D. It receives its motion from the gear-wheel B'. Upon the other side of this pulley B² is permanently 80 attached a second clutch, b'. This is adapted to engage with the pin b², which latter is driven through the center of the shaft. When the clutch b' is engaged with the pin b² it causes the shaft D to turn with the pulley B² and 85 carry with it the pulley D', which is permanently attached upon one end of the shaft. Upon the other end of this shaft D is permanently attached the pulley D², adapted to engage with the gear-wheel D³. This large gear-wheel, in turn, is permanently attached to the 90 shaft H, upon which is permanently attached the spool H'. To operate this last pulley B² with its clutch b and b', I attach the lever I. This lever is pivoted at any suitable point, 95 but preferably to a cross-bar upon the top of the frame, and is attached to the pulley in any suitable manner. By manipulating this lever the spool operating the sand-pump may be set in motion and stopped; so, also, the device for 100 raising the drill. Upon the spool H' is wound the rope or chain used in supporting and op-

erating the drill. It is connected with the drill by passing over the pulley K, under the small pulley E² at one end of the walking-beam, from thence over the pulley K', and from 5 thence to the drill.

The object of the use of the two pulleys K and K', in combination with the pulley E², is to enable the drill L to be raised or lowered through a space equal to twice that through which the 10 small pulley E² traverses at the same time. Upon one side of the frame I attach the rod M. Upon one end of this rod is a worm-gear adapted to engage with a pinion, D'. Upon its other end is a crank for operating the same. 15 The office of this rod, with its crank and connection, is to permit the lowering of the drill without the use of other machinery and without stopping its operation. This is done simply by turning the crank, which, in turn, causes 20 the worm-gear to engage the pinion D', which, being permanently attached to the shaft, turns the pinion D², which, in turn, operates the large gear-wheel D³ upon the shaft H, to which is permanently attached the spool H', carrying the rope or chain used in raising and lowering the drill. To the same side of the frame is attached the rod N. This rod at one end is permanently attached to the spring N'. This spring N' is connected with the worm-gear upon the rod M. When it is desired to 25 lower the drill L faster than can be done by turning the crank M', the worm-gear is disconnected from the pinion D' by pushing forward the rod N, which, in turn, operates the spring N', to which is connected the worm-gear. This loosens all braking mechanism between the spool H' and the drill L, when the latter 30 will drop by gravity. It can be arrested at any point by releasing the pressure upon the rod N, when the spring N' will force the worm-gear to engage with the pinion D'. 35

Having thus described the construction of my invention, the operation is as follows: The machine being placed in position at the point 40 desired for drilling the well, the drill L is lowered to place. Power is then applied to the shaft B, when, at each revolution thereof, the cam C raises one end of the walking-beam E, when the other end is lowered, carrying 45 with it the pulley E². As this is lowered it raises the drill L. If the fall of the drill L at each stroke is not sufficient it may be increased by lowering the walking-beam E by manipulating the screw in the fulcrum F by 50 means of the crank F'. If, on the other hand, the fall is too great, it may be lessened by raising the fulcrum in the same manner. When 55 it is desired to lower the drill a short distance, it is done by applying power to the crank M'

upon the rod M. When it is desired to raise 60 the drill from the well for the purpose of clearing it out, the pinion B², with its clutch b', is crowded toward the pinion D' by means of the lever I, when the clutch b' engages with the pin b². This will set in motion the shaft 65 D, which, through its gearing and a large gear-wheel, D³, will turn the spool H' and raise the drill. If it is now required to operate the sand-pump, the clutch b is engaged with its counterpart g upon the spool G. When the 70 sand has been removed from the well, and it is desired again to operate the drill, it may instantly be lowered to the bottom of the shaft by bearing against the spring N', through the rod N, when the worm-gear upon the end of 75 the shaft M becomes disengaged from the pinion D'. This releases the spool H', and the drill L drops by gravity to the bottom of the well.

What I claim is—

1. In a well boring and drilling machine, the combination, with a walking-beam, of a vertical screw-shaft provided with a vertically-adjustable frame or block, to which the walking-beam is pivoted, substantially as set forth. 80

2. In a well boring and drilling machine, the combination, with a vertically adjustable walking-beam, of a cam arranged to engage with one end of said walking-beam and actuate the same, substantially as set forth. 85

3. In a well boring and drilling machine, mechanism for feeding the drill, consisting of an endless screw operating upon a pinion, the latter connected by suitable gearing with the spool, substantially as and for the purpose 90 shown. 95

4. In a well boring and drilling machine, the pinion B², provided with clutches, whereby power may be applied to operate the rope-spool or the sand-spool, substantially as and 100 for the purpose shown.

5. In a well boring and drilling machine, the combination, with suitable mechanism for feeding the drill, consisting of an endless screw operating upon a pinion, the latter connected by suitable gearing with the spool, of 105 mechanism whereby the endless screw may be thrown out of engagement and the drill permitted to drop, substantially as and for the purpose shown.

In testimony whereof I have signed my name to this specification in the presence of two subscribing witnesses.

CHARLES HARMON.
